UNITED STATES PATENT OFFICE

2,153,516

ELECTRICALLY OPERATED LIFTING JACK

Karl Eck, Avalon, Pa., assignor to The Duff-Nor-ton Manufacturing Company, Pittsburgh, Pa., a corporation of Pennsylvania

Application November 2, 1937, Serial No. 172,358

15 Claims. (Cl. 254—98)

This invention relates to lifting jacks which are operated by electric motors to raise and lower the load.

It is an object of the invention to provide an improved electrically-operated lifting jack, and one that can be operated by inexperienced persons without the possibility of ever overrunning the set limits of movement.

It is customary to provide a limit switch of some form to cut off the power to the motor when the jack approaches its upper or lower limit of movement. When the jack is wired in such a way that the motor turns in the wrong direction, the limit switches may be ineffective. For example, if the motor is running with the wiring such that a down movement against the limit switch is required to cut off the power supply, but the direction of rotation of the motor is causing the jack to rise, then the switch means can not operate automatically to stop the jack from moving too far.

Such a situation may arise because of a mistake in originally wiring the jack, but in the case of portable jacks which are "plugged in" to a power line wherever they happen to be used, the direction of rotation of the motor may be reversed by a change in the polarity of the power line connections. In a three-phase motor the exchanging of any two wires will reverse the motor.

With stationary machinery the electrician that installs the machinery must, by trial, find the proper connections for the various wires. This can hardly be expected in the case of a portable tool. This invention makes such trials unnecessary by providing a phase-changing switch that operates if the motor does not rotate in the right direction to make the limit switches effective.

Other objects, features and advantages of the invention will appear or be pointed out as the specification proceeds.

In the accompanying drawings, forming part hereof:

Fig. 1 is a front elevation, partly broken away and partly in section, on the line 1—1 of Fig. 2, showing a jack embodying this invention;

Fig. 2 is a side view partly in elevation with the gear case cover removed and partly in section approximately on the line 2—2 of Fig. 1;

Fig. 3 is an enlarged sectional view of the switch box, most of the section being taken on the line 3—3 of Fig. 2;

Fig. 4 is a detail view of a part of the structure shown in Fig. 3, illustrating its method of operation;

Fig. 5 is an enlarged sectional view taken on the line 5—5 of Fig. 1; and

Fig. 6 is a wiring diagram of the jack shown in the other views.

The jack comprises a frame 11 having a base 12 and bearings in which slides a lifting head or ram 14. The ram has a nut 15 through which threads an actuating screw 16 supported by the base 12. A bevel gear 18 connected to the bottom portion of the screw 16 is rotated by a smaller bevel gear 20 on a horizontal shaft 21 with a large spur gear 22 (Fig. 2). A key 23 fastened in the frame 11 keeps the ram 14 from rotating.

Power to drive the gear 22 is supplied by an electric motor 24 through the reduction gearing shown in Fig. 2. There is a small gear 25 on the motor shaft, and both a small and a large gear on each of three shafts 27, 28 and 29, the small gear on each shaft meshing with the large gear on the next shaft so as to reduce the speed and increase the force of the rotary motion transmitted from the motor to the screw 16.

There is a brake drum 31 on the motor shaft, and a brake shoe 33, supported on a pivot 34, is held against the brake drum 31 by a spring 36 with sufficient force to keep the gearing and motor from turning when the power to the motor is shut off.

A push rod 38 is loosely held in bearings 39. An adjustable shoulder 40 threads over one end of the push rod 38 and can be held in set position by a lock nut 41. The push rod 38 extends through an upstanding end of the brake shoe 33 which is held against the shoulder 40 by a spring 42 surrounding the end portion of the push rod.

The other end of the push rod 38 forms a blunt point that fits into a V notch 44 in the face of a cam 45. This cam is secured to a shaft 46, and the shaft is oscillated by a link 47 connected at its lower end to a crank 48 of the shaft 46 and at its upper end to a lever 49, best shown in Fig. 1.

The lever 49 is secured to one end of a shaft 51. This shaft extends through a switch box 52 and projects through the front face of the switch box. A handle 54 fastened to the projecting end of the shaft 51 is moved into different positions to control the operation of the jack. In Fig. 1, the handle 54 is shown in its middle, neutral position. The free end of the handle 54 is raised to cause the jack to rise and is pushed down to cause the jack to lower, as indicated by legends "Up" and "Down" on the cover of the switch box.

A block 56 fastened to a lever 57 extends into a groove 58 in the side of the ram 14. The ends of the groove 58 (Fig. 2) form abutments 60 and 55

61 which strike the block 56 to move it whenever the ram 14 approaches the lower and upper limits of its travel.

Referring again to Fig. 1, the lever 51 has a fulcrum 63 at one end, and is connected at its other end with the lever 49 by a link 65. This connection causes the handle 54 to move when the block 56 on lever 51 is shifted up or down by the abutments 60 and 61 on the ram 14.

- 10 If the handle 54 is in the "down" position when the abutment 60 comes against the block 56, the link 65 is pushed down and the handle 54 is raised into the neutral position shown in the drawings. With the handle 54 in its "up" position, movement of the block 56 by the abutment 61 as the ram approaches the limit of its upward movement raises the link 65 and shifts the handle 54 down into neutral position.

This movement of the link 65 causes the link 47 to move in the same direction and rotate the shaft 46. When the handle 54 is in neutral position, the link 47, shaft 46, and cam 45 will be in the positions shown in Fig. 2 with the notch 44 in line with the push rod 38. When the end of the rod is in the notch 44, the brake shoe 33 is against the drum 31 and the brake is applied. Any angular movement of the cam 45 in either direction causes the sloping sides of the notch 44 to thrust the push rod 38 toward the left and release the brake. Thus, the brake is applied only when the handle 54 is in neutral position, and the design of the cam 45 is such that it releases the brake before the switches of the motor circuit have moved far enough to close. The brake can be operated only through the cam 45.

The structure enclosed in the switch box 52 is shown in Figs. 2-5. Referring first to Fig. 2, there is a cam 67 rigidly held on the shaft 51 by a set-screw 68. Two switch arms 69, 70 on the shaft 51 are free to turn on the shaft 51 but are yieldably held in a predetermined angular relation with the shaft 51 and cam 67 by spring pins 72 (Fig. 3) which slide in recesses in the switch arms and project into a notch 73 in the cam 67.

The switch arm 69 carries a block 74 made of insulating material. A spring 75 which urges the pin 72 against the cam 67 is compressed between the pin 72 and block 74 and is strong enough to bring the switch arm 69 back to its normal angular relation with the cam 67 and shaft 51 whenever the switch arm is moved and the pin 72 displaced upward along the sloping sides of the notch 73.

A contact 76 extends through the block 74 and a side contact 77 connects with the contact 76. This side contact 77 rubs against a stationary plate 79 (Fig. 2) secured to an insulating frame 80 fixed to the switch box 52. The off-side location and action of the spring 75 in arm 69 holds side contact 77 against the plate 79. There are other contacts on the frame 80 in position to be touched by the contact 76 when the switch arm 69 moves. These other contacts are best shown in Fig. 3 and include a contact 82 against which the contact 76 comes when the switch arm 69 is moved clockwise and a contact 83 in position to limit counterclockwise movement of the switch arm contact 76.

The construction of the switch arm 70 (Fig. 2) is similar to that of the switch arm 69 except that its spring and its side contact are on the other side. Reference characters 86, 87, 89, 92 and 93 are used to indicate the contacts for switch

arm 70 which correspond with the contacts 76, 77, 79, 82 and 83, respectively. Not all of the contacts for switch arm 70 can be seen in Figs. 2 and 3, but they are indicated in the wiring diagram (Fig. 6).

Referring again to Fig. 3, the cam 67 has recesses 95, 96 and 97 with raised portions 98 and 99 between these recesses, and flanks 100 and 101 beyond the outer recesses. A plunger 103, urged toward the cam 67 by a spring 104, has a conically shaped and rounded end which enters any of the recesses 95, 96 or 97 to hold the cam 67 and the shaft 51 in any one of three angular positions, corresponding to the "up," "down," and neutral positions of the handle 54 (Fig. 1) by which the shaft 51 is turned. The movement of the cam 67 from notch 96 to 95 is greater than that required to close contact 76 against contact 82 in order to insure a good electrical contact, and on opening the switch the contact 76 will remain against the contact 82 because of the spring action of pin 72 until the plunger 103 enters the recess 96 and effects a quick movement of the switch arm into neutral position. A similar action is obtained when the switch is closed in the other direction.

There is a cross shaft 106 (Fig. 3) below the plunger 103, and there is a gear segment 107 fixed on the shaft 106 and meshing with teeth on the bottom of the plunger. A crank arm 109 has its upper end formed into a clamp 110 which grips one end of the cross shaft 106.

A ratchet case 112, best shown in Fig. 4, turns about a shaft 113 and is connected with the crank arm 109 by a link 114. The full-line positions of the parts in Fig. 4 correspond with the neutral position of the shaft 51. When the cam 67 is in the position shown in broken lines, the lower flank 100 of the cam pushes the plunger 103 back and causes the teeth on the plunger to turn the gear segment 107 and move the crank arm 109, link 114 and ratchet case 112 into the positions shown in broken lines. The movement of the ratchet case amounts to ninety degrees in Fig. 4.

A pawl 116 carried by the ratchet case 112 turns a ratchet 117 in a counter-clockwise direction. The ratchet is connected with the stem of a rotary snap-switch 119 (Figs. 3 and 5) which requires a full quarter-turn to cause it to snap. If the ratchet case turns less than a quarter-turn and then backs to neutral position, the pawl 116 and the ratchet back to their original positions without operating the switch. The details of the switch construction are not shown, rotary snap-switches being well known in the art, but Fig. 3 shows four contacts or brushes 121, 122, 123 and 124 bearing against contact segments 125 and 126 on a rotatable disc 128 which is made of insulating material. When the switch 119 snaps, the disc 128 turns a quarter revolution. In the positions shown in Fig. 3, the contact segment 125 connects the brushes 121 and 124, and the segment 126 connects the brushes 122 and 123, but when the disc has moved ninety degrees the segments on the disc connect brushes 121 and 122 and connect brushes 123 and 124. Another quarter turn connects the same brushes as shown in the drawings. The switch 119 operates as a phase-changing or polarity-changing switch.

Fig. 6 is a wiring diagram showing the control circuits of the three-phase motor 24. This motor has three terminals 131, 132 and 133. The terminal 131 is connected directly with the power line. Each of the other motor terminals is connected

with two of the stationary contacts on opposite sides of the frame 80. The contact plates 79 and 89 are connected with brushes 123 and 121, respectively. The other brushes 122 and 124 connect directly with the power line.

Fig. 5 is a sectional view looking from a plane near one end of the switch box 52. This view shows a panel 140 with fuse clips 141, 142 and 143 and connections to the motor and switch conductors. A fuse 145 is shown in each clip. Conductors lead from each of the fuse clips to a polarized connection 147 for an extension cord.

The operation of the jack will be reviewed briefly. When the control handle 54 is in the neutral position shown in Fig. 1, the switch arm 69 (Fig. 2) and the other switch arm 70 immediately behind it are in a neutral position between the contacts 82, 83, 92 and 93 (Fig. 6) and no power is supplied to the motor. The brake remains set, so that if the jack is raised and under load the weight of the load can not turn the operating mechanism and lower the jack.

When the control lever is pushed up, it turns the shaft 51 (Fig. 3) clockwise and brings the recess 95 into line with the plunger 103 so that the pressure of the plunger will hold the shaft 51 and its connected parts in their new position. In this position the switch arm 69 holds the contact 76 against the fixed contact 82 and the other switch arm holds the contacts 86 and 92 (Fig. 6) together. There is then a circuit from the terminal 132 of the motor through contacts 82, 76 and 77 to plate 79, and from this plate through brush 123, segment 126 and brush 122 to the power line. The terminal 133 of the motor connects with the power line through contacts 92, 86, 87, plate 89, brush 121, segment 125, and brush 124.

If these circuits cause the motor to rotate in a direction to raise the jack, then the ram will rise until the control lever is manually shifted to neutral position or until the abutment 61 (Fig. 1) on the lower portion of the jack strikes the block 56, lifts the link 65 and crank 49 so that the shaft 51 is turned back to neutral position. If these circuits cause the motor to rotate in a direction to lower the jack and the ram is already near its lowest position, then the upper abutment 60 will push the block 56 down and cause the shaft 51 to turn clockwise beyond its normal "up" position.

The effect of this abnormal movement is shown in Fig. 4. As the shaft 51 and cam 67 turn clockwise, the flank 100 thrusts the plunger 103 further and further back and causes the gear segment 107 to turn and rock the crank 109 into the broken-line position shown. By the time the crank 109 reaches this position, the ratchet cage 112 has made a quarter revolution and caused the switch to snap into a position in which the segment 125 (Fig. 6) connects contacts 121 and 122, and a circuit between contacts 123 and 124 is closed by the segment 126. The change in the positions of the segments 125 and 126 connects the motor terminals 132 and 133 with different wires of the power line and effects a reversal of the motor.

In the event that the motor turns in the wrong direction when the control lever is moved to its "down" position, the shaft 51 (Fig. 4) is turned counter-clockwise until the flank 101 of the cam 67 pushes the plunger 103 back and effects a reversal of the motor in the same way as when the cam turns into the broken-line position already explained. The phase-changing switch 119 can

be manually operated by moving the control handle 54 (Fig. 1) far enough to turn the shaft 51 and cam 67 (Fig. 4) into the position shown in broken lines or the corresponding position on the opposite side.

The preferred embodiment of the invention has been described, but changes and modifications can be made, and some features of the invention can be used without others.

I claim:

1. A lifting jack including an electric motor and mechanism operated by the motor to raise or lower the jack depending upon the direction of rotation of the motor, switch means controlling the supply of power to the motor, and a control lever which causes the motor circuit to be open when said lever is in a neutral position, and switch means in the motor circuit which cause the motor to operate in opposite directions when the lever is shifted to opposite sides of said neutral position, and which reverse the motor if shifted further in the same direction.

2. The improvement in electric motor-operated lifting jacks which comprises switch means controlling the supply of power and the direction of operation of the motor, and a switch-operating member movable to either side of a neutral position to cause the motor to operate in one direction or the other, and connections effective to reverse the motor upon further movement of said member in either direction away from the neutral position.

3. The combination with a lifting jack having an electric motor, of two reversing switches connected in the circuit of said motor in such a manner that shifting of either switch changes the direction of operation of the motor, a switch operating member which operates one of said switches when moved to either side of a neutral position, and means actuated by said member to operate the other switch when the operating member is moved to either side of its neutral position for a distance substantially greater than necessary to operate the first switch.

4. The combination with a lifting jack having a reversible electric motor, of two switches in the motor circuit including a first switch that has an open position but closes in either direction from said open position to cause rotation of the motor one way or the other, and a snap-switch effective to change the direction of rotation of the motor, a switch operating lever for the first switch, and connections actuated by said lever to operate the snap-switch when said lever moves in either direction for a substantial distance further than necessary to close the first switch.

5. In a lifting jack having a three-phase motor, a switch for shutting off the power supply to the motor, circuits that cause operation of the motor in different directions when the switch is closed on opposite sides of the neutral position, and a phase-changing switch in the motor circuit and operable to change the direction of movement of the motor while the first switch remains closed on either side of its neutral position.

6. A lifting jack comprising a ram, operating mechanism for said ram including an electric motor, a switch controlling the supply of power and the direction of operation of the motor, a switch-operating handle movable to opposite sides of a neutral position to operate the switch to start the motor in one direction or the other, a second reversing switch in the motor circuit,

connections through which the switch-operating handle shifts the second reversing switch if moved in either direction for a substantial distance further than necessary to close the first switch, and automatic means actuated by the ram as it approaches the limit of its travel for operating the switches in the same sequence as the handle operates said switches.

7. In an electrically-operated lifting jack, a ram, automatic stop means for stopping further movement of the ram when it reaches certain positions near the upper and lower limits of its travel, and automatic reversing means for preventing further movement of the ram beyond said stop positions in the event that said automatic stop means fail to stop the ram.

8. In a lifting jack having a ram operated by an electric motor and automatic stop means for opening the motor circuit when the ram reaches predetermined limits of travel in either direction, the improvement of a reversing switch in the motor circuit, and means effective to operate said reversing switch if the automatic stop means fail to halt the movement of the ram at said predetermined limits.

9. In a lifting jack having a ram and operating mechanism driven by a three-phase motor, means actuated by the operating mechanism for opening the motor circuit as the ram approaches its upward limit of travel, means actuated by the operating mechanism for opening the motor circuit as the ram approaches its downward limit of travel, and apparatus operated by the jack-operating mechanism to interchange the circuits of the limit means when the motor operates in the wrong direction to make said limit means effective.

10. The combination with a lifting jack having operating mechanism driven by an electric motor, of a control circuit with automatic limit switch means for stopping the operating mechanism at predetermined positions in the upward and downward movement of the jack, and other automatic switch means which change the control circuit if the motor operates in a direction that makes the limit switch means ineffective.

11. A lifting jack comprising a ram and operating mechanism for the ram including an electric motor, switches in the motor circuit including a limit switch actuated by the operating mechanism as the ram reaches its normal

limit of travel, and another switch actuated by the operating mechanism when the ram moves beyond its normal limit of travel.

12. A lifting jack including a ram, operating mechanism for the ram, an electric motor that drives said operating mechanism, a switch that opens the motor circuit when said switch is in neutral position and closes a circuit which causes the motor to operate in one direction or the other when moved to either side of neutral position, abutments connected with the ram, a block connected with the switch and located in the path of the abutments, and a second switch operated by said abutments to change the circuits of the first switch if said abutments move the block in the wrong direction to stop the motor.

13. In a portable lifting jack having a three-phase electric motor and an extension cord for connecting the motor with a source of power, the combination of a limit switch and an abutment which shifts the limit switch to stop the motor when the jack approaches its limit of travel in one direction, and a phase-changing switch operated by movement of the limit switch in the wrong direction by said abutment.

14. In a lifting jack including an electric motor and mechanism operated by the motor, a control handle movable into three positions, a switch operated by said handle to open the circuit when the handle is in mid-position and to cause the motor to operate in opposite directions when shifted to either side of mid-position, a mechanical brake for holding the mechanism against movement when the switch is in open position and the motor is not energized, and connections through which the brake is controlled by the same handle that operates the switch, said connections being effective to release the brake before the switch closes in either direction.

15. In a lifting jack operated by an electric motor, a control-switch movable to either side of an open, neutral position to cause operation of the motor in either direction, a polarity-changing switch in the motor circuit, a brake for stopping the motor and holding it against rotation when the motor circuit through the switches is open and there is no power in the motor, and a common control handle that operates both of the switches and said brake.

KARL ECK.
